UNITED STATES PATENT OFFICE.

REESE W. FLOWER, JR., AND EDWARD C. BURGESS, OF PHILADELPHIA, PENNSYLVANIA, ASSIGNORS TO THE UNITED STATES AUTOMATIC GAS MACHINE COMPANY, OF NEW JERSEY.

GAS-MACHINE.

SPECIFICATION forming part of Letters Patent No. 253,028, dated January 31, 1882.

Application filed April 14, 1881. (No model.)

To all whom it may concern:

Be it known that we, REESE W. FLOWER, Jr., and EDWARD C. BURGESS, both citizens of the United States, and residents of the city and county of Philadelphia, and State of Pennsylvania, have invented a new and useful Improvement in Gas-Machines, which improvement is fully set forth in the following specification and accompanying drawings, in which—

10 Figure 1 is a side elevation, partly sectional, of the gas-machine embodying our invention. Figs. 2 and 3 are views of detached portions thereof.

Similar letters of reference indicate corresponding parts in the several figures.

Our invention consists of a valve which opens at the proper time to permit the exhaust of the generator.

It also consists of novel means for operating 20 the supply-pump of the generator.

It also consists of means for preventing the forming of an air-cushion and a vacuum in the generator.

It also consists of a pipe communicating with 25 the air-chest of an air-pump and the exhaust-pipe of the generator, whereby air is continuously intermixed with the vapor, and the gas thus forced to the place of service.

Referring to the drawings, A represents the 30 vaporizing-chamber or gas-generator, which is of the form of a tube or cylinder supported upright on the frame B of the machine, and surrounded by a water-jacket, C.

Within the generator A is a plunger or piston, D, the stem E of which has connected to 35 its upper end the piston F of an air-pump, G, which is properly mounted on a platform supported on the standards B' of the frame B.

Communicating with the air-chest G' of the 40 pump G is an air-conveying' pipe, H, with which latter also communicates a pipe, J, leading from the interior of the generator A.

Attached to the stem E, outside of the generator, is a collar, K, which is provided with 45 an arm, K', having a boss or sleeve, K'', through which passes loosely the stem L of a valve, M, the shell of which rises from the base of the generator A or the frame B and communicates with the pipe J, said stem L having secured to

it stop-collars L', one of which is located at the 50 upper end of the stem and the other between the ends of the stem, so that there is a collar above and below the boss K'' of the arm K'.

N represents a pipe, which forms a communication between a pump, P, and the base of 55 the generator A, said pump being properly located and supported and leading from a tank or other place of supply of hydrocarbon or other proper fluid or oil.

The pump-rod Q has connected to its upper 60 end a cord or chain, R, which passes around a grooved wheel or pulley, S, and carries at the end opposite to the connection with the pump-rod a weight, T. The pulley S is suitably suspended or supported by means of a yoke or other bearing, U, connected to the top platform or one of the standards B', and has secured to one face a segmental ratchet, V, with which is adapted to engage a pawl, W, pivoted to the yoke U. An upright rod or pin, X, is passed through a 65 horizontal eye, X', projecting from the yoke U, below the pawl W, and so disposed that when elevated it may strike said pawl from below and raise it clear of the ratchet V, said pin being pivoted to one end of a lever, Y, which has 70 its axis on the yoke U, its other end being secured to the collar K of the stem E by means of a slotted connection, as at a, said lever Y being adapted when raised to strike the ratchet V.

The water-jacket C surrounds the sides and base of the generator A, the bottom or portion of said jacket below the base of the generator being shown at C'; and below said bottom C' is located the heating device Z, consisting in 85 the present case of a series of gas-jets arranged in annular form.

The operation is as follows: The gas-jets are lighted, so that the water in the jacket is heated, thus heating the generator A. To start the 90 machine the pump P may be operated by hand to inject a supply of fluid or oil into the generator. The oil is immediately converted into vapor, the impulse of which elevates the piston D. As the stem E rises it lifts the lever Y 95 and arm K'. The lever Y comes in contact with the ratchet V and rotates the pulley S, and the end of said lever, carrying the pin X,

descends, thus lowering said pin and permitting the pawl W to drop on the ratchet, which latter rides freely past the pawl until the lever has reached its highest point. The sleeve K'', 5 ascending with the arm K', strikes the upper stop-collar, L', and raises the plug or piston of the valve M. The vapor in the generator now enters the pipe H, where it joins a volume of air forced into said pipe H by the action of the o ascending piston F of the air-pump G, and thus the gas is forced to the place of service. The rotation of the pulley S by the action of the lever Y, as has been stated, lowers the chain on the side connected to the pump-rod, 5 and the latter descends as one motion of said pump. The weight of the piston F of the air-pump now causes the descent of the stem E and piston D of the generator, and as the lever Y leaves the ratchet V the pawl W engages with the ratchet—in the present case the right-hand tooth—and prevents rotation of the pulley S. The descent of the stem E brings the sleeve K'' against the lower stop-collar, L', thus closing the valve M, any remaining vapor 5 in the generator being forced out into the pipe J by the descending piston D just in advance of the closing of the valve. As the stem E descends it lowers the lever Y and gradually raises the pin X, which latter at the proper moment disengages the pawl W from the ratchet V, whereby the weight T becomes operative and causes the rotation of the pulley S, so as to raise the pump-rod Q as another motion of the pump, and immediately a supply of oil is ejected or forced into the generator, where it is vaporized, and the succeeding operations are similar to those hereinbefore stated.

The base of the generator is widened or flaring and grooved on the upper face of its bottom plate, whereby a large heating and vaporizing surface is obtained, and the water-jacket conforms to the shape of the base, so that every important part of the generator is heated.

The pump G is double-acting, two of its 5 valves opening from the atmosphere and two opening into the air-chest G', so that on both the ascent and descent of the piston F air is forced into the chest, and thus continuously directed into the pipe H, where it joins the o vapor from the pipe J, and so the gas passes uniformly to the place of service.

The stem E of the pistons D F is hollow and perforated, so that it communicates with the generator A and barrel or cylinder of the air-pump, respectively, above and below said pistons. Should there be air in the generator above its piston D, when the latter ascends 5 the air is caused to enter the hollow stem E,

and so reaches the barrel of the pump, overcoming the formation of an air-cushion in the 60 generator, whereby the ascent of the piston D is not retarded. When the pistons are ready to descend, the air may again enter the stem E and reach the generator through the hollow stem, thus preventing the formation of a 65 vacuum in said generator, or relieving the latter of such, if formed. The stem E is common to both pistons D F, and the construction and location of all parts are such that the machine is simple and compact in its nature. 70

The water-jacket has an inlet, b, for replenishing it with water, and an opening, c, for escape of steam.

We are aware that it is not broadly new to surround a gas-generator with a water-jacket 75 which applies hot water to the enlarged bottom and to the sides of said generator; also, that it is not broadly new to employ levers, rods, chains, pawls, and weights, in combination with the piston-rod of a generator and 80 the source of supply of said generator for governing the supply of gasoline; and that it is not new to utilize the hollow rod of a pump-piston for the passage of gas from a generator below the pump. We do not claim any of such 85 constructions.

What we do claim is—

1. The generator A, in combination with the valve M and pipe J, and the connected piston-rod E and valve-stem I, substantially as 90 and for the purpose set forth.

2. The generator with its piston-rod and a connected arm, in combination with the pump mechanism consisting of the pump-rod, chain, pulley, pawl and ratchet, and weight, said 95 weight operating reversely to said piston-rod of the generator in turning said pulley, substantially as and for the purpose set forth.

3. The pulley, pump-rod, and weight, in combination with the ratchet V, pawl W, rising- 100 and-falling pin X, and mechanism for operating said pin, substantially as and for the purpose set forth.

4. The generator and air-pump, in combination with a communicating hollow piston-rod, 105 substantially as and for the purpose set forth.

5. The gas-generator and an air-pump, in combination with a pipe communicating with the air-chest of said pump and the exhaust or discharge pipe of the generator, substantially 110 as and for the purpose set forth.
